UNITED STATES PATENT OFFICE

126,777

DESIGN FOR A UNIFORM DRESS OR THE LIKE

Leo M. Cooper, Yonkers, N. Y.

Application August 29, 1940, Serial No. 94,706

Term of patent 3½ years

To all whom it may concern:

Be it known that Leo M. Cooper, a citizen of the United States and resident of Yonkers, in the county of Westchester and State of New York, has invented a new, original, and ornamental Design for a Uniform Dress or the like, of which the following is a specification, reference being had to the accompanying drawing, forming part thereof, in which,

Fig. 1 is a front view of a uniform dress embodying my new design; and

Fig. 2 is a rear view thereof.

I claim:

The ornamental design for a uniform dress or the like, substantially as shown.

LEO M. COOPER.
